UNITED STATES PATENT OFFICE.

JOHN GEMMIL, OF MERCER COUNTY, PENNSYLVANIA.

RADIATOR.

Specification of Letters Patent No. 11,481, dated August 8, 1854.

To all whom it may concern:

Be it known that I, JOHN GEMMIL, of the county of Mercer and State of Pennsylvania, have invented a new and useful Improvement in Radiators; and I do hereby declare that the following is a full, clear, and exact description of the construction and operation of the same, reference being had to the annexed drawing, forming part of this specification, in which—

Figure 1 is an elevation of the radiator and Fig. 2 is a section through the axis of the same, on line $\alpha\alpha$ of Fig. 1.

Similar characters of reference in the several figures denote the same part of the apparatus.

My invention is designed to prevent the great loss of heat which is occasioned by the ordinary construction of stove pipes, in consequence of the passage of the current through the pipe, in obedience to the known laws of heat, without producing the amount of radiation which a more favorable construction would afford.

It consists in placing upon the stove, in the situation usually occupied by the first two joints of pipe, a radiator of the form of two frustums of cones joined at their bases, and in suspending within this case a deflector and regulator consisting of an inverted cone, and right frustum united at their bases; said deflector and regulator being lined with some non-conducting substance, and movable vertically as will be hereafter fully set forth.

To enable others skilled in the art to make and use my invention I will proceed to describe its construction and operation.

In the drawing A is the casing formed of two frustums of cones united at their larger bases, the smaller base B of the lower frustum fitting upon the stove and the other smaller base fitting the pipe. Within this cone is the deflector and regulator C suspended by the chain α passing over the pulley b on the shaft c , which shaft is rotated by the crank d , and is held in any desired position by the ratchet f and pawl e . This deflector and regulator consists of an inverted cone D and right frustum E united at their bases, the cone and frustum having a lining h of some non-conducting substance. The relative proportions of the several parts

are as follows: The diameter of the largest portion of the case is to the diameter of the pipe, as fifteen is to seven, and the ratio of the base of the cone D to the greatest diameter of the case as eight to fifteen, though these proportions need not be rigidly adhered to. In the lower portion of the case A is a small draft channel m closed by a door n ; this is only designed for use when the chimney is low and the draft impeded, as in back buildings and other similar situations.

The operation of my improved radiator is as follows—The heat passing from the stove will by meeting the vertex of the cone D be deflected, and the central portion of the current which would otherwise pass upward without producing any effect upon the casing will be brought into contact with the surface of the case and impart a large portion of its heat to the same, which will be diffused through the apartment by radiation. This economy of heat by bringing into effective action a portion of the current which is usually suffered to escape, causes a proportional decrease in the quantity of fuel required to produce a given amount of heat in an apartment, which saving in fuel has by experiment been found to be at least fifty per cent.

The non-conducting casing h prevents the absorption of heat by the deflector and permits the full effect of the column to act upon the radiating casing. The draft is regulated by the position of the deflector within the case, said deflector being raised and lowered by the turning of the shaft c as set forth in the drawings.

What I claim as my invention and desire to secure by Letters Patent, is—

The suspension within a radiating case substantially as described, of a deflector and regulator constructed, arranged, and operating, substantially as set forth, for the purpose specified.

In testimony whereof, I have hereunto signed my name before two subscribing witnesses.

JNO. GEMMIL.
